UNITED STATES PATENT OFFICE.

HARMON E. LINDBLADH, OF BOSTON, MASSACHUSETTS.

PEN-CLAMP FOR RULING-MACHINES.

1,392,423.

Specification of Letters Patent.

Patented Oct. 4, 1921.

Application filed October 21, 1918. Serial No. 258,996.

To all whom it may concern:

Be it known that I, HARMON E. LINDBLADH, a citizen of the United States, residing at Boston, in the county of Suffolk and State of Massachusetts, have invented a new and useful Pen-Clamp for Ruling-Machines, of which the following is a specification.

In ruling machines, the ruling pens are ordinarily held in place in their beam between a clamping jaw fixed to the beam and a movable jaw secured to the companion jaw by a series of bolts. Since the cloths delivering ink to the pens rest on the upper side of the beam and extend over the clamp, the thumb nuts by which the jaws are tightened to grasp the pens are necessarily on the under side of the clamp. Because of this, when the operator desires to position the pens in setting them to rule a form, the beam must be turned upon its supports until nearly vertical to give access to the nuts so they may be loosened and tightened to enable the pens to be shifted and held in their new positions. But with the beam thus raised, if the bolts are sufficiently loose to allow all the pens to be readily adjusted, those which have been brought to the proper position are liable to become displaced. The movement of the beam incident to the final tightening of the clamp may also disarrange the pens. By the present invention I provide means for actuating the clamp in its normal or horizontal position with uniform pressure throughout its pen-engaging length, and which effects the application of the entire clamping force simultaneously by a single operating member.

The accompanying drawing illustrates 40 two of many forms which my invention may assume,

Figure 1 being a broken front elevation of one embodiment of the invention;

Fig. 2, an end elevation looking from the 45 left in Fig. 1;

Fig. 3, a transverse section on the line 3—3 of Fig. 1;

Fig. 4, a view, similar to Fig. 1, of a modification of the invention; and

Fig. 5, an end elevation of the organization of Fig. 4.

There is shown in the drawing the forward portion of the beam of a ruling machine having a relatively fixed upper jaw 10 recessed to receive a clamping plate 11, 55 which is secured to the upper wall of the recess by screws 12. The movable jaw of the clamp is furnished by an opposite or lower plate 13 guided in its movement toward and from the upper plate by pins 14 fixed in the beam and extending loosely through openings in the plate 13. These jaws or clamping plates are adapted to engage and hold in properly spaced relation the shanks of 60 ruling pens 16, which may be of the usual form. To operate the movable jaw 13, a member, shown as a rod 17, is mounted below the beam in a position parallel to the plates. I have shown it as carried by supports or brackets 18 which may be distributed at intervals beneath the clamp, there preferably being one near each extremity of the series of pens. Each bracket 65 has an upwardly extending arm 19 fixed to the plate 11, as by riveting, and passing 70 through slots 20 in the plate 13. The brackets are flanged at 21 to furnish ways in which move actuating blocks 22 secured to the rod 17 by set-screws, as shown, or 75 in any other suitable manner. Each block 80 has an inclined upper cam face 23 contacting with an oppositely inclined face upon the lower extremity of a projection 25 depending from the plate 13. It will be seen, that if the blocks are moved by the travel of the 85 rod axially beneath the projections, the latter and the plate 13 will be raised or lowered with relation to the companion plate 11, so the two plates may be either caused 90 to clamp the shanks of the pens between them or to release the pens for their adjustment or removal. To accomplish this movement of the rod, I prefer to provide it at one extremity with a thread, shown at 95 26, this thread being engaged by a correspondingly threaded sleeve 27 held against shifting longitudinally of the rod by an annular flange 28 turning between arms 29, 29 at the bottom of a bracket 30 fixed to the extremity of the beam by screws 31. At the 100 outer end of the sleeve is mounted a bevel pinion 32 meshing with a similar pinion 33

fast upon the lower end of an operating shaft 34 extending vertically transversely of the beam, this shaft being journaled in a lug 35 on the bracket 30. The shaft may be rotated by a finger piece 36 fixed at its upper extremity, and may be secured in position by a set screw 37 threaded through the wall of the lug and contacting with the shaft 34. Upon the thread 26 appear a nut 10 and check nut 38 which may be set to limit the movement of the rod 17 to the left, as viewed in Fig. 1 of the drawings, these preventing the projections 25 from riding off the ends of the cam surfaces 23.

15 In using the device, the operator, with the beam in its normal position, may turn the shaft 34 by the finger piece until, through the gearing 32, 33 and the threaded engagement of the sleeve 27 and rod 17, the blocks 20 22 are so positioned that their cam faces allow the plate 13 to be moved by gravity out of contact with the companion plate 11, leaving a space between the plates sufficient to admit the shanks of the pens. These are 25 then inserted between the plates in substantially the proper relation for the particular form to be ruled and the clamp is tightened enough to engage them frictionally, while still permitting them to be further adjusted.

30 They may then be brought to their final positions and firmly clamped, at which time the shaft 34 is fixed against rotation by the set screw 37. It is to be observed, that since elements by which the clamping mechanism 35 is operated are all beyond the end of the beam and clear of the ink cloths, said beam may remain in its normal horizontal position so there will be no force tending to disarrange the pens during their final positioning. Then, when the lower plate is raised 40 by the clamping mechanism to fix the pens, the force is applied evenly throughout the length of the clamp and without any jar tending to disturb the arrangement.

45 Another form of my invention appears in Figs. 4 and 5 of the drawing. Here the clamping members are the same as in the first three figures, but instead of the rod 17, a shaft 39 is employed mounted in bearings 50 40 depending from the plate 11 and passing through slots in the plate 13. Distributed along the shaft, they preferably being closely adjacent to the bearings to prevent spring of the shaft, are cams 41, here shown as 55 spaced from one another by considerable intervals, though obviously they may be elongated to any desired extent. At one end of the shaft is fastened an arm 42 extending upwardly beside the beam, opposite which 60 is a screw 43 threaded through the arm. The operation of setting and securing the pens is generally as already described, the movement of the arm and eccentrics to the right, as viewed in Fig. 5, separating the 65 lower clamping plate from the upper to per-

mit the insertion of the pen shanks, while movement in the opposite direction clamps them, this position being maintained by bringing the screw 43 into contact with the end of the beam.

70

I claim:

1. A pen-clamp for ruling machines comprising a relatively fixed jaw, an opposed movable jaw, supports extending from the fixed jaw to points outside the movable jaw, 75 and an actuating member for the movable jaw mounted to move longitudinally of the jaws upon the supports at the exterior of the movable jaw.

2. A pen-clamp for ruling machines comprising an upper jaw, a lower movable jaw provided with openings, supports depending from the upper jaw through the openings and beneath the lower jaw, means individual to the respective supports for attaching them to such upper jaw, and an actuating member for the lower jaw mounted to move upon the supports longitudinally of the jaws.

80

3. A pen-clamp for ruling machines comprising an upper jaw, a lower movable jaw having downward projections with inclined lower faces, supports depending from the upper jaw beneath the lower jaw, and a member mounted to move upon the supports 90 and having inclined faces coöperating with those of the lower jaw.

95

4. A pen-clamp for ruling machines comprising an upper jaw, a lower movable jaw having downward projections with inclined lower faces, supports depending from the upper jaw beneath the lower jaw, a member mounted to move upon the supports and having inclined faces coöperating with those of the lower jaw, and means carried by the 100 member for limiting its movement.

105

5. A pen-clamp for ruling machines comprising an upper jaw, a lower movable jaw, supports depending from the upper jaw beneath the lower jaw, and an actuating member mounted to slide upon the supports, 110 there being inclined coöperating surfaces upon the lower jaw and actuating member.

110

6. A pen-clamp for ruling machines comprising relatively movable jaws, an actuating member mounted to travel along the jaws and being provided with a threaded portion, a rotatable nut engaging the thread to effect the travel of the actuating member, means for preventing the movement of the 120 nut longitudinally of the jaws, and a shaft journaled upon a jaw and geared to the nut.

115

7. A pen-clamp for ruling machines comprising relatively movable jaws, an actuating member mounted to travel along the jaws 125 and being provided with a threaded portion, a rotatable nut engaging the thread to effect the travel of the actuating member, a rotatable shaft geared to the nut, and means for fixing said shaft against rotation.

130

8. A pen-clamp for ruling machines comprising relatively movable jaws, an actuating member mounted to travel along the jaws and being provided with a threaded portion, a rotatable nut engaging the thread to effect the travel of the actuating member, and means carried by the threaded portion

to limit the travel of said actuating member.

Signed at Boston, in the county of Suffolk and State of Massachusetts, this ninth (9th) day of October, 1918.

HARMON E. LINDBLADH.
